G. E. THACKRAY

BONDING RAILS

Filed April 14, 1921

UNITED STATES PATENT OFFICE.

GEORGE E. THACKRAY, OF WESTMONT BOROUGH, PENNSYLVANIA.

BONDING RAILS.

Application filed April 14, 1921. Serial No. 461,352.

My invention relates to bonding rails, with particular reference to a simple and easily applied type of flexible bond the terminals of which are fused or welded to the upper 5 surface of the base flanges of the rails in order to provide a connection between the ends of abutting rails which is both mechanically strong and electrically conductive to an extent equal to the capacity of the 10 flexible bond. The flexible bond portion of my construction and the parts of the terminals to which it is attached are preferably located under the rail flanges so that the bond is protected from distortion or 15 destruction by derailed cars, and as the ends of the terminals on the rail flanges are small and flat and with beveled edges if necessary, will not cause any obstruction to the passage of the wheels and can not be destroyed 20 by a derailed car.

My invention also relates to the method of applying said bonds to the rails, and although I have shown and illustrated my terminals secured to the upper portions of the 25 base flanges of the rails they may be secured to any other portions of the rails to which they are applicable, as will be readily understood.

My bond consists of a pair of terminals 30 each of which is of hook form, the upper portion being adapted to rest upon the upper surface of the base flange of a rail, while the other end of the hook or clip is adapted to receive a flexible cable preferably formed 35 from a number of strands of copper wire or laminae which are secured within the sockets formed in the terminals either by compressing or by being forced therein, after which they may be brazed or soldered, or the ends 40 of the cable may be fused to and within the terminals. If the ends of the cable are fused or welded in the terminals only the end portions thereof should be so secured and the other portion of the bond connected 45 with the part between the terminals should not be so fused, and the edges of the holes in the terminals should be preferably rounded so that the weaving action of the rails due to traffic would not cause the edges of the 50 terminal to cut the bond, and as the material of the flexible bond where it issues from the terminal is in its original condition and has not been heated or made brittle by welding it will withstand such slight bending 55 due to the movement of the rails without being destroyed thereby. The terminals

which are used are preferably made of malleable iron castings which resemble iron or steel and which are of metal somewhat similar to the rails which they connect and can 60 therefore be easily secured thereto by fusion or welding either by electric pencils and arc or by acetylene and oxygen or other blow-pipe flames. In certain cases, however, I 65 may make my terminals of iron, steel, bronze, brass, copper or other metal as will be readily understood. My terminals are preferably formed with holes or notches therein, the edges of which are adapted to form part of the joint and to neatly receive 70 additional fusing metal and make a neat job of connecting them to the rails, although I may, if desired, use some fused metal around the other edges of my terminal to make a 75 more secure connection, but this ordinarily 75 is not needed. I also prefer to so locate and arrange my bonds that the flexible portion is normally slack or curved between the terminals to allow for the expansion and contraction of the rails and for the relative 80 movement of the rail ends by traffic in such a way that the bonds will not be harmed in any manner by such movement.

In prior cases where bonds are not flexible and are secured to abutting rail ends 85 the relative movement of the rails causes their constant flexure and subjection to undue stresses so that they would, in a measure, try to serve as splice bars at the rail joints, to which use, however, such structures 90 are not at all adapted, and this would result in their relatively quick destruction, all of which is obviated by my type of flexible bond.

Another advantage of my bond formed 95 and applied in this way is due to the fact that the contact of the terminal with the rail is localized and the material of the bond terminal is comparatively strong so that when it is desired to remove the bonds from the rail this can be done by striking the terminal with a hammer or by placing a flat-nosed tool against the bond and hitting it with a hammer or sledge, whereupon the 100 fused material can be sheared off, and after the hole or notch is cleaned again the bond can be used elsewhere. This is particularly 105 convenient in mines or in cases where the rails of the track have to be taken up and replaced elsewhere.

The lower portion of my bond terminal 110 may be spaced apart from the bottom of the

2
rail flange and the terminal may be held in place while being connected by a pair of pliers, a spring clip or a wooden or metal wedge driven between it and the rail, or by 5 customary clamps.

Having thus given a general description of my invention, I will now, in order to make the matter more clear, refer to the accompanying sheet of drawings forming 10 part of this specification in which like characters of reference refer to like parts:

Figure 1 is a side elevation of the meeting ends of a pair of rails united by an angle splice bar and bolts with the ends of the 15 lower flange of the angle splice bar cut away, to form recesses exposing the upper surfaces of the rail flange, with one form of my improved bond shown in place connecting the ends of the rails. This form is desirable 20 when a comparatively short and economical bond is wanted, as the portions of the splice bar which are to form recesses cut away do not detract from its strength, while the flexible cable of the bond is shorter and consequently 25 cheaper. Figure 2 is a vertical transverse sectional elevation taken on the line II—II of Figure 1. Figure 3 is a side elevation of the meeting ends of a pair of rails united by angle splice bars and bolts 30 similar to Figure 1, but without the ends of the lower flange of the angle splice bar cut away, with my improved bond is shown in place connecting the ends of the rails. This type of bond is longer than the one illustrated 35 in Figure 1 and is designed for use with angle splice bars the ends of the flanges of which are not cut away, this bond, however, being somewhat longer and heavier and consequently more expensive than the one 40 illustrated in Figure 1. Figure 4 is a vertical transverse sectional elevation taken on the line IV—IV of Figure 3. Figure 5 is a side elevation of the meeting ends of a pair of rails united by plain splice bars or 45 fish plates with a very short bond shown in place connecting the ends of the rails. This bond is a very short and consequently inexpensive type of construction, and as illustrated is flexed between terminals so as to 50 allow for contraction and expansion of the rails and slight movement thereof without effecting the bond for reasons previously stated herein. Figure 6 is a vertical transverse sectional elevation taken on the line 55 VI—VI of Figure 5. Figure 7 is a bottom plan view of the meeting ends of the rails showing the bond illustrated in Figures 5 and 6 in place thereon. Figures 8, 9, 10, 11, 12, 13, 14 and 15 illustrate slightly different 60 forms of my terminals and ways of attaching them to the flanges of the rails. Figure 16 illustrates two different ways of holding the bond terminal to the flange of the rail while fusing or otherwise securing the terminal to the base flange of the rail. In this

view the extreme end of the rail has been cut away so as not to hide the wedge and the lower part of the terminal and cable. Figures 17 and 18 illustrate on a larger scale two different ways of forming the 70 fused or other connection between the flange of the rail and the bond terminal.

Referring now to the various characters of reference on the drawings: 1 is the end of one rail, 2 the end of the adjacent rail, 3 75 are the rail flanges, 4 and 5 are the angle splice bars illustrated in Figures 1 and 2, the ends of the flanges 6 being cut away as illustrated in order to provide recesses or spaces for the bond terminals and to accommodate a shorter bond, and 7 are the splice bolts illustrated in Figures 1 and 2. The upper portion of the terminal is provided with a hole 9 either drilled or otherwise formed therein and when in position on the 80 rail this may be filled or partly filled with material similar in composition to the terminal and the rail and this is preferably introduced in the form of an electric pencil which pencil may be of soft steel or iron or other metal through which a current of electricity is passed in the usual manner and which 85 fuses the pencil, but at the same time slightly fuses the surface of the rail and the terminal adjacent thereto and provides a strong mechanical and electrical union of these two portions. This, as previously explained, 90 may also be accomplished by acetylene or other blow-pipe flame either with or without added metal.

The bonding material is fused into a hole or notch in one member of the terminal which contacts with the rail so that the terminal is electrically secured to the rail in a substantially integral manner and by reason of so fusing the bonding material in the hole or notch, which is relatively smaller than the member in which it is formed, the fused material has a less area of 105 cross section in the plane of contact with the rail than the member of the terminal itself, whereby a forcible movement of the terminal in said plane, as elsewhere described herein, will shear the bonding or fused material without harming or distorting the terminal, which when cleaned or partially cleaned of the remnant of fused material, can be used again.

The removal of the terminal can thus be 110 easily and simply accomplished although the electric bond between the parts is good and sufficient when the terminal is secured in place by the fused metal in the notch or opening thereof.

The fused material being placed in the hole or notch of the terminal is thus concentrated and this in a measure, determines its size and area and also adds to the neat and mechanical appearance of the structure.

As illustrated in Figures 1 and 3, 10 is 120

the bond cable, preferably formed of copper wires twisted together or it may be of copper or other laminae of good conducting material, and the terminals are provided with 5 openings 11 in which the ends of the cable are secured in any of the manners previously described. 12 are the angle splice bars illustrated in Figures 3 and 4, 13 are the splice bolts therefor and 14 are the bond terminals 10 illustrated in Figures 3, 4, 5, 6, 7, 8, 16, 17 and 18 in which the upper portion of the terminal engages with and is adjacent to the top of the rail flange while the lower portion of the terminal is provided with a 15 space 15 between it and the bottom of the base flange. 16 are plain splice bars or fish plates illustrated in Figures 5 and 6, 17 is the bond cable shown in Figures 5 and 7, 18 are the splice bolts shown in Figures 5 20 and 6, and 19 is the upper portion of the bond terminal illustrated in Figure 9.

Referring to Figures 8 to 15 inclusive, 14, 19, 21, 23, 25, 27, 29 and 31 are the upper portions of the bond terminal which are 25 respectively provided with circular hole 9, the rectangular hole 20, the open-ended rectangular notch 22, the corner rectangular notch 24, the corner quarter-circle shaped notch 26, the two circular holes 28, the two 30 corner notches with rounded corners 30 and the two approximately semi-circular notches 32, and the terminal metal forming the walls or part of the walls of each of the holes or 35 notches may be fused as before described together with the adjacent portions of the rail surface with or without added metal, whereby the terminal is secured to the rail in an efficient manner both mechanically and electrically.

40 As illustrated in Figure 18 the opening which is preferably made of tapering form is not filled with added metal, but the edges 33 of the terminal may be fused to and with a portion of the rail flange without adding 45 any metal, although generally I prefer to add metal as before described.

Referring now to Figure 16 the terminal 14 may be held in position prior to and while securing the same to the rail by means 50 of a wedge 34 which may be of metal or wood, driven between the base of the rail flange and the lower part of the terminal hook as illustrated, or it may be held in place by the spring clip 35. In addition to

securing the bond terminal to the rail 55 through the notches or openings therein I may also secure the edges of the upper portion of the terminal itself as indicated at 37 in Figures 8 and 9, and I may also, instead of making the ends of the terminal with 60 square corners, make them round, as indicated by the dotted lines 36 in Figure 8.

As illustrated in Figure 12, 38 is a flat-nosed tool provided with a handle, the flat end of which may be placed against the 65 upper portion of my hook terminal, and when struck by a hammer or sledge this will shear off the fused connecting metal in the notch 26, and as the terminals are made of strong material and of ample size, the 70 terminals themselves will not be distorted, but the bond may thereby be easily removed from the rail. After this is done the fused metal may be cut out of the notch and the 75 band used again elsewhere.

Although I have described and illustrated my invention in considerable detail, I do not wish to be limited to the exact and specific details thereof as shown and described, but may use such modifications in, substitutions 80 for, or equivalents thereof, as are embraced within the scope of my invention, or as pointed out in the claim.

Having thus described my invention, what I claim and desire to secure by Letters Patent is:—

In a rail bond, a terminal of open hook form, one part or the upper portion of the hook of which is adapted to rest upon the upper surface of a rail flange, the other and lower portion of the hook being adapted to underlie the said rail flange and out of contact therewith, an opening or notch in the upper hook member of said terminal of less cross sectional area than that of said member in the plane of contact between it and the rail; metal of composition similar to that of said terminal and the rail deposited in a fused condition in said notch or opening while the adjacent metal of the 95 terminal and rail are partially fused or heated, thereby securing the terminal to the rail, and a flexible cable electrically and mechanically secured within the lower portion of said hook-formed terminal.

In witness whereof I hereunto affix my signature.

GEORGE E. THACKRAY.
